UNITED STATES PATENT OFFICE.

ELIJAH DIXON, OF EMPORIA, KANSAS.

IMPROVEMENT IN HARNESS-SADDLES.

Specification forming part of Letters Patent No. 128,025, dated June 18, 1872.

Specification describing a new and Improved Adjustable Harness-Saddle, invented by ELIJAH DIXON, of Emporia, in the county of Lyon and State of Kansas.

In my improved saddle the parts, except two adjusting plates, are made flexible above the backbone, and these adjusting-plates lap each other thereat, and the lapping parts are formed on two circular curves, and the holes through the plates for the screws which confine all these parts together are elongated, so that said plates may be shifted along said screws when they are unfastened for adjusting the saddle for flat or sharp backed animals, and when the screws, terrets, and water-hook are screwed up the saddle will be rigidly secured or adjusted.

Figure 1 is a longitudinal sectional elevation of a harness-saddle constructed according to my improvement. Fig. 2 is a cross-section on the line $x x$ of Fig. 1, and Fig. 3 is a top view of the adjusting and fastening plates.

Similar letters of reference indicate corresponding parts.

The strong pieces of wood or leather, A, or other substance forming the base or tree on which the saddle is built, are not rigidly connected together at the top, and over them and the leather B by which they are covered I place a stiffening-plate, D, on each side, with long slotted holes for the screws E, terret-

screws F, and the water-hook H, so that said plates can shift along said screws and be confined by them when they are screwed down. These plates are formed on a true circle at the upper ends, which extend entirely over the top portion of the saddle and lap each other throughout the length of the circular parts, and one has a headed stud, I, which works in a dovetail-shaped slot, K, in the other, to keep the two plates in position when they are not clamped by the screws. The other parts of the saddle are flexible over this jointed part of the plates, so that when the screws are loosened the pads may be readily adjusted toward or from each other to suit the shape of any horse, and when so adjusted the screws fasten and retain them as required, thus making a simple and efficient adjustable saddle.

Having thus described my invention, I claim as new and desire to secure by Letters Patent—

The combination, with the flexible portion of the saddle, as described, of the adjusting-plates D, arranged to secure the said flexible part rigidly by the terret, water-hook, and other screws, substantially as specified.

ELIJAH DIXON.
